(57) **CLAIM**

The ornamental design for a drawstring pouch having eight peripheral pockets, as shown and described.

DESCRIPTION

FIG. 1 is a top view of a drawstring pouch having eight peripheral pockets showing my new design and shown in its flattened state prior to pulling on the drawstring;

FIG. 2 is a side view thereof;

FIG. 3 is a top perspective view thereof, shown with pockets having been formed by pulling on the drawstring;

FIG. 4 is a side view of the pouch shown in FIG. 3;

FIG. 5 is a top view of the pouch shown in FIG. 3;

FIG. 6 is a sectional view taken in the direction of the arrows upon the line 6—6 of FIG. 5; and,

FIG. 7 is a bottom view of the pouch shown in FIG. 4.
